US0D1063038S

(12) **United States Design Patent** (10) Patent No.: **US D1,063,038 S**
(45) Date of Patent: ** Feb. 18, 2025

(54) **WALL-MOUNTED AROMATHERAPY MACHINE**

(71) Applicant: **Shenzhen Zhianyi Technology Co., Ltd.**, Guangdong (CN)

(72) Inventor: **Angli Zhan**, Guangdong (CN)

(**) Term: **15 Years**

(21) Appl. No.: **29/876,176**

(22) Filed: **May 17, 2023**

(51) LOC (15) Cl. **23-04**

(52) U.S. Cl.

CLAIM

The ornamental design for a wall-mounted aromatherapy machine as shown and described.

DESCRIPTION

FIG. 1 is a front perspective view of a wall-mounted aromatherapy machine showing my new design.

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear, bottom perspective view thereof.

The broken lines in the drawings depict portions of the wall-mounted aromatherapy machine that form no part of the claimed design.

1 Claim, 8 Drawing Sheets
